UNITED STATES PATENT OFFICE.

ANDREW KUBICKI, OF WEBSTER, MASSACHUSETTS.

ADJUSTABLE FIRE BOX.

Application filed December 4, 1922. Serial No. 604,640.

To all whom it may concern:

Be it known that I, ANDREW KUBICKI, a citizen of the United States, residing at Webster, in the county of Worcester and State of Massachusetts, have invented a new and useful Adjustable Fire Box, of which the following is a specification.

This invention relates to a fire box capable of general use, but particularly useful in connection with a coal or wood range.

The principal objects of the invention are to provide means whereby the effective size of the fire box can be varied to permit of its use for a relatively small fire when desired in order to use a fuel more concentrated than that ordinarily used or to economize in the amount of fuel consumed and not necessitate the employment of the whole fire box and the consequent full charge of fuel; and also to provide for this adjustment in a simple manner which will not interfere with the use of the range in the ordinary way and with a full charge of fuel. The invention also involves the division of the fire box in two ways which can be used independently of each other or in co-operation if desired. I have shown them used in the same structure. Additional objects and advantages of the invention will appear hereinafter.

Reference is to be had to the accompanying drawings in which

Fig. 1 is a longitudinal sectional view of a part of a coal range showing a preferred embodiment of this invention applied thereto;

Fig. 2 is a longitudinal sectional view of the fire box on the line 2—2 of Fig. 1;

Fig. 3 is a fragmentary plan of the adjustable grate;

Fig. 4 is a fragmentary side view of one of the supporting legs enlarged showing the grate applied thereto;

Fig. 5 is a fragmentary vertical sectional view of the same on the line 5—5 in Fig. 4;

Fig. 6 is a fragmentary horizontal sectional view on the line 6—6 in Fig. 4;

Fig. 7 is an enlarged fragmentary end view looking in the direction of the arrow 7 in Fig. 2, showing the means for reducing the length of the fire-box; and

Fig. 8 is an enlarged fragmentary view similar to part of Fig. 2, but showing the end partition drawn up out of the way of the grate.

I have shown the invention as applied to

an ordinary coal range having a fire-box lined with fire brick 10 at the front and rear ends, and having the usual oscillating or rotating dumping grate 11.

For the purpose of reducing the effective depth of the fire-box I provide a series of legs 13 preferably four in number each having a foot 14 adapted to rest on the bottom wall of the fire-box that projects beyond the fire-brick. These legs are located near the four corners of the fire-box and each one is provided with a plurality of key-hole shaped slots 15. The several slots in the several legs are located at the same elevation, and they are arranged to support undercut inset projections 16 on a removable auxiliary grate 17. The legs therefore do not project beyond the grate.

The grate is shown as having a series of parallel long perforations 18 and a series of circular perforations 19, either of which can be used alone throughout the area of the grate. It is designed to be located in elevated position supported by these legs, so that a small amount of coal or wood can be used upon it directly under the lid openings for the purpose of getting the necessary amount of heat with considerably less fuel than would be used with the entire fire-box in operation, and to concentrate the fire directly under the lid opening so that the heat will be more effectively applied. This grate can extend throughout the whole length of the fire-box if desired, but I have shown it used in cooperation with another feature, so that it appears as extending throughout only a part of its length.

The additional feature which I have mentioned consists of a device for cutting off the effective length of the fire-box. This is a metal plate 20 arranged vertically in the fire-box near one end. It is provided with a wire supporting bale 21 pivoted in lugs 22 on its back extending across it, and having its arms rounded at the top and projecting up so as to rest on the rounded upper edge of the top of the fire brick. This is intended to support the removable plate 20 in vertical position and cut off the length of the fire-box so as to limit the amount of fuel used whether the grate 17 is used or not.

In order to prevent the draft being allowed to pass up beyond the plate 20 I pivot to its bottom a sheet metal or other plate 24 adapted to be located horizontally beyond the plate 20 and cut off the draft. This

plate 24 fills the entire space beyond the plate 20 in which no fire is to be built and no fuel is to be located.

This, of course, is used in connection with the oscillating or rotating grate 11 and that grate has to swing in the usual manner so that it is necessary to provide for moving the plates 20 and 24 out of the way before that can be done. For this purpose a link 25 is pivoted to the plate 24 at about its center and is connected with a flat operating hook 26 pivoted to the plate 20. This operating hook 26 has an elbow 27 for connection with the link 25 and a loop 28 beyond it for the operator to take hold of with a finger for manipulating the parts. It also has a rounded end 29 adapted to engage the plate 20.

When it is desired to operate the grate 20 the user grabs the hook in the most convenient position as shown in Fig. 2, and swings it up to the position shown in Fig. 8 to get the plate 20 up out of the way of the turning grate, so that the ashes can be dumped or the like. Then he turns it back again, the whole thing being supported on the bale 21 all the time, and it is ready for operation again.

Although I have illustrated and described only a single form of the invention I am aware of the fact that modifications can be made therein by any person skilled in the art without departing from the scope of the invention as expressed in the claims. Therefore I do not wish to be limited to all the details of construction herein shown and described, but what I do claim is:—

1. In a device of the character described, the combination with a plate adapted to be placed in a fire box to cut off the effective length thereof, of a plate connected to the first named plate and adapted to be located in position to prevent draft behind the first named plate, a handle connected with one plate, and means connected with the handle and with the other plate for swinging the horizontal plate upwardly and simultaneously swinging the vertical plate to inclined position to permit operation of a dumping grate below.

2. In a device for the purpose described, the combination of a removable grate having near its edges a series of undercut inset lugs, and the same number of legs, each having a keyhole slot for receiving one of said lugs.

3. In a device for the purpose described, the combination with a fire box, of a removable grate having near its four corners

a series of undercut inset lugs and the same number of legs, each having a keyhole slot for receiving one of said lugs, said legs having feet extending inwardly at their lower ends, and each being bent inwardly at the point at which the slots are located to space it from the sides of the fire box.

4. The combination with a fire box, of an auxiliary grate therefor, and means located near the four corners of the grate for removably supporting said grate in adjusted vertical positions in the fire box, said grate extending only part way from one end of the fire box to the other, a plate located at the end of the grate in vertical position to reduce the effective length of the fire box, and a bale connected with said plate extending up from it at front and rear to hold the plate in position.

5. The combination with a fire box and a dumping grate extending the length thereof, of an auxiliary grate above the dumping grate, adjustable and detachable and extending only part way from one end of the fire box to the other, a horizontal end plate beyond the end of the auxiliary grate, and means for moving the end plate beyond the range of the dumping grate in order that it may be turned.

6. The combination with a fire box, of a vertical plate located therein for reducing its effective length, a bale pivoted to the rear of said plate and having arms extending up at the front and rear of the fire box to engage over the fire-brick lining thereof at the top and hold the plate in position, and means pivoted at the bottom of the plate for preventing a draft up through the fire box beyond the plate.

7. In a device of the character described, the combination with a plate adapted to be placed in a fire box to cut off the effective length thereof, of a bale pivoted to the rear thereof, and having means for supporting the plate from the front and rear sides of the fire box, an imperforate plate pivotally connected to the bottom of the first named plate and adapted to be located in horizontal position to prevent draft behind the first named plate, a link connected with the horizontal plate, and a handle pivoted to the vertical plate and to the link for swinging the horizontal plate upwardly and the vertical plate to inclined position to permit operation of a dumping grate below.

In testimony whereof I have hereunto affixed my signature.

ANDREW KUBICKI.
